LAWN MOWER HOUSING

William R. Smith, McDonough, Ga., assignor to
McDonough Power Equipment, Inc.

Filed Mar. 13, 1968, Ser. No. 10,951

Term of patent 14 years

(Cl. D40—1)

FIG. 1

FIG. 4

FIG. 2

FIG. 3

FIG. 5

FIG. 6

FIG. 7

FIGURE 1 is a perspective view of a lawnmower housing illustrating my new design as seen from the right front end thereof;

FIGURE 2 is a top plan view of the lawnmower housing;

FIGURE 3 is a bottom plan view of the lawnmower housing;

FIGURE 4 is an elevational view of the lawnmower housing as seen from its right side;

FIGURE 5 is an elevational view of the lawnmower housing as seen from its left side;

FIGURE 6 is an elevational view of the lawnmower housing as seen from its front end; and

FIGURE 7 is an elevational view of the lawnmower housing as seen from its rear end.

I claim:

The ornamental design for a lawnmower housing, substantially as shown.
